UNITED STATES PATENT OFFICE.

HUBERT K. WOOD, OF HARTFORD, CONNECTICUT.

FLOAT-VALVE.

SPECIFICATION forming part of Letters Patent No. 578,672, dated March 9, 1897.

Application filed January 9, 1896. Serial No. 574,828. (No model.)

To all whom it may concern:

Be it known that I, HUBERT K. WOOD, a citizen of the United States, residing at Hartford, in the county of Hartford and State of Connecticut, have invented certain new and useful Improvements in Float-Valves, of which the following is a specification.

This invention relates to valves of that class more particularly designated as "float-valves" and more especially applicable to water-closet tanks; and the object of the invention is to provide an automatically-operable valve simple in construction and effective in operation.

15 A further object of this invention is to provide a valve in which the hissing of the water and the hammering and rattling of the valve usually found in devices of this character are obviated.

20 A further object of this invention is to provide a valve of such simplicity of structure that the cost of construction thereof is materially lessened, while its effectiveness in operation is increased.

25 In the drawings accompanying and forming part of this specification, Figure 1 is a side elevation of a valve, illustrating one embodiment of my present invention. Fig. 2 is a vertical partly-sectional view thereof, the 30 valve-actuating lever being broken off; and Fig. 3 is a horizontal top sectional view taken on line *a a*, Fig. 2.

Similar characters designate like parts in all the figures of the drawings.

35 My invention is herein shown embodied in a structure adapted for use with flushing-tanks of water-closets, and for the purposes of this specification it will be described with such object in view; but it will be understood 40 that the invention is not alone designed for flushing-tanks of water-closets, but is applicable also to many other structures in which a valve of a similar character of operation to the one herein shown and described, whether 45 automatically or otherwise operable, may be used.

My invention comprises generally a suitable valve casing or body (designated in a general way by *A*) having communicating 50 inlet and outlet ports or passages, a valve-

chamber in the nature of a reaction-chamber and into which the outlet-port opens and a valve-seat adjacent to the outlet port or passage, a valve member (designated in a general way by *B*) embodying a valve disposed in 55 said valve-chamber and means for guiding and regulating the movement of said valve in said chamber, and an actuating-lever in operative connection with said valve member for actuating the same.

In the preferred form thereof herein shown and described the valve casing or body *A* is preferably of differential diameters, forming thereby substantially three chambers *c*, *d*, and *e*, and which chambers are herein designated, for the purposes of this specification, as the "piston cylinder or chamber" *c*, the "inlet-chamber" *d*, and the "reaction or outlet chamber" *e*, and this reaction-chamber has its walls curved or concaved, whereby, 65 when the fluid strikes the same, it will be caused to react toward the center of the chamber in a manner hereinafter set forth. It will be understood, however, that the casing may be constructed in any other suitable way, 70 with or without the differentially-dia metered chambers, and that the chambers thereof need not necessarily be of differential diameters relatively to each other. For instance, the inlet-chamber *d* may be of substantially the 75 same diameter as the piston-chamber *c*; but it is believed that the casing or body can be more quickly and easily constructed and the object of my invention more readily accomplished by the use of a casing or body con- 80 structed to substantially form three chambers, and hence while not in all instances nec- 85 essary, yet for the purposes of this specifica- 90 tion and the better description of my invention it has been so described and illustrated.

The valve casing or body has an inlet port or passage 10 and an outlet port or passage 11. The inlet-port 10 preferably opens into the middle or inlet chamber *d* at one side thereof and above the reaction-chamber *e* and 95 the outlet-port, while said outlet-port 11 leads from the inlet-chamber *d* and opens into the reaction-chamber *e* and is preferably formed by an inwardly-extending circular flange 12, forming a valve-seat 13 at its under side, the 100

circular wall 14 of said flange constituting a guiding means for the valve member throughout its entire operation in a manner herein-after set forth.

5 The inlet-port 10 is substantially of less area than the outlet-port 11, whereby a reduction of pressure is obtained adjacent to such outlet-port.

The walls of that portion of the valve cas-
10 ing or body adjacent to the inlet-port 10 prefer-
ably flare and gradually unite with the walls
of the inlet-chamber *d*, which preferably
bulges above the outlet-port, so that the
water or fluid can be forced substantially
15 around said enlarged chamber and flow into
the reaction-chamber *e* from all points of said
inlet-chamber, whereby the fluid will have a
direct downward movement rather than an
oblique or sidewise movement, as would be
20 the case if the water flowed through the out-
let-port at that point thereof nearest the in-
let-port without being first forced around the
chamber.

The valve or valve member *B* in the form
25 shown preferably comprises a valve proper,
15, disposed in the reaction-chamber *e* and
adapted to engage the valve-seat 13, a pis-
ton-rod 16, extending through the inlet-cham-
ber *d* and entering the piston-chamber *c*, and
30 a piston 17', disposed in said chamber *c*.

The piston-rod 16 has a threaded end 17
and an annular flange or shoulder 19 within
the reaction-chamber and a slotted and
threaded end and an annular flange or shoul-
35 der 20 in the piston-chamber, and which
flanges 19 and 20 are preferably integral with
the piston and form supporting means for
suitable packings. The slotted and threaded
end of the piston-rod may be separate there-
40 from, if desired.

The valve 15 in the form shown comprises
a suitable packing (herein shown in the nature
of a leather disk 21) secured in position ad-
jacent to the flange 19 and adapted to engage
45 the valve-seat 13 and an interiorly-threaded
clamping-nut 22, engaging the threaded end
17 of the piston-rod 16, for securing said pack-
ing in position relatively to the flange 19, and
50 which nut is herein shown as a conically-
shaped nut for the purpose hereinafter set
forth, and, if desired, may have suitable means
whereby the same can be quickly and easily
placed in position on the piston-rod or re-
55 moved therefrom, such, for instance, as a
thumb-piece or pin-holes.

At that end of the piston-rod 16 which ex-
tends into the piston-chamber *c* the piston 17'
is secured, and in the form shown is in the
nature of a cup-shaped packing 23, secured
60 thereto adjacent to the flange 20 by means of
a suitable interiorly-threaded nut 24, engag-
ing the threaded portion 18 of the piston-rod
for clamping said packing in position. This
cup-shaped packing forms a tight joint with
65 the wall of the piston cylinder or chamber *c*,

whereby the outflow of water at this point
from the inlet-chamber *d* is prevented.

As one means for guiding the valve and
also for regulating the action of the same the
piston-rod 16 is provided, intermediate of its
70 piston and valve and at that point thereof
in its movement which is contiguous to the
wall 14 of the outlet-port 11, with radial wings
or flanges 26, preferably shown herein as
75 three in number, which wings 26 are adapted
to closely engage the wall of the outlet-port
in the opening and closing movements of the
valve, whereby said valve is not only steadied
80 in its action, but by the close engagement of
the wings or flanges with said wall the action
of the valve is thereby regulated to prevent
the too quick closing and seating of the same,
relatively to its seat, on the upward motion
85 of the actuating-lever, whereby the hammer-
ing action usually appertaining to valves of
this character and which is believed to be
due mainly to the quick-closing action of the
valve when near its seat is obviated. These
90 wings or flanges 26 are cut away or inwardly
beveled, as at 27, to thereby form an annular
recess intermediate of the valve and said
wings or flanges, whereby the divided streams
hereinafter described will unite into one
95 stream at the top of the valve when said
valve is adjacent to its seat, to thereby pre-
vent the hissing sound, also usually found in
valves of this character, in a manner herein-
after set forth.

The actuating-lever 30, which in the con-
struction shown is adapted to carry a float,
100 (not shown,) has its inner end extending
through a slot 31 in the piston-rod, and is
pivotally secured to an extension 32 of the
valve casing or body *A*, and works in said
slot to actuate the valve member *B* on the
105 rise and fall of the float in a manner that
will be obvious without a more explicit de-
scription.

If it is desired that the water be conducted
to the bottom of the tank rather than have
110 a drop fall, the lower end of the reaction-
chamber *e* may be constructed with a threaded
extension for the reception of a pipe in a
manner that will be obvious without the ne-
cessity of illustration or further description
115 and without in any wise affecting the opera-
tion of this device.

In the operation of my improved valve the
fluid enters through the inlet-port 10 and is
forced around the inlet-chamber *d*, and on
the opening of the valve it flows downward
through the outlet-port, being divided into
120 three separate and distinct streams and
caused to spread and engage the curved or
concaved wall of the reaction-chamber *e*,
125 whereby, owing to the peculiar construction
of such chamber, said streams are returned
toward the center of the chamber, one part
thereof counteracting the other part thereof
and all acting toward and uniting at such cen-
130

ter, whereby a new and distinct stream is formed at this point, which flows from the reaction-chamber through its discharge-opening 12' in one compact and undivided stream. 5 The fluid on its rebound or reaction toward the center of the chamber engages the conically-shaped face of the valve, and acts, during the closing operation of said valve, to assist in such closing operation.

10 The hissing sound usually appertaining to valves of this character and which, it is believed, is ordinarily due to the action of the valve during its closing movement and when it has nearly reached its seat, by permitting 15 the fluid to be discharged in a small stream at a few places only of the outlet-port and thus causing such hissing sound, is obviated in my improved construction, owing to the fact that when the valve has nearly reached 20 its closing movement the fluid, owing to the cut-away or beveled portions 27 of the wings or flanges, which form an annular recess intermediate of the valve and of said wings or flanges, is permitted to flow entirely around 25 the upper portion of the valve, and hence escapes in a relatively large stream or sheet at all places adjacent to the valve-seat, whereby the discharge of a small stream at any one place and the consequent hissing of the wa- 30 ter are obviated, as the valve closes and seats itself, while the water is discharged entirely around the same in a sheet and not at any one place.

By means of my improved construction of 35 valve the same can be made at a relatively low cost without in any wise impairing its efficiency and in the use of which the hissing sound and the hammering and rattling action of the valve are entirely overcome, as has

been found by experience with a valve constructed in accordance with this description. 40

In practice that portion of the casing constituting the piston-cylinder *c* in which the piston 17' works may be made of slightly larger area than the area of the outlet-port 45 11, whereby, owing to the increased pressure adjacent to the piston as compared with that adjacent to the outlet-port, the valve may be at all times firmly seated and balanced in its movements. 50

Having thus described my invention, I claim—

A valve comprising a valve casing or body having an inlet-port, an outlet-port, and a valve-seat; a reaction-chamber below and 55 with which said outlet-port communicates, said chamber having concaved walls and a discharge-opening; a valve disposed in the reaction-chamber and adapted to engage the valve-seat and provided with radial wings or 60 flanges engaging the walls of the outlet-port for regulating the movement of said valve, said wings or flanges having their lower ends cut away or beveled adjacent to the upper face of the valve to form an annular recess 65 intermediate of said valve and the flanges or wings and in proximity to the valve-seat when said valve is about to engage the same, to thereby permit the fluid divided by said wings or flanges to unite into one stream or sheet 70 around the top of the valve when the same is closing on its seat and thus prevent the hissing of the same; and means for actuating the valve. 75
